UNITED STATES PATENT OFFICE.

HARRY I. WILLIAMS, OF DECATUR, TEXAS.

SASH-FASTENER.

SPECIFICATION forming part of Letters Patent No. 380,237, dated March 27, 1888.

Application filed November 26, 1887. Serial No. 256,263. (No model.)

To all whom it may concern:

Be it known that I, HARRY I. WILLIAMS, of Decatur, in the county of Wise and State of Texas, have invented a new and useful Improvement in Sash-Fasteners, of which the following is a specification.

My invention relates to sash-fasteners for holding and locking a window-sash either in an open or closed position; and it consists in the combination of a ratchet-bar attached to the sash, a grooved or hollow bar attached to the window-frame and bearing a spring-pawl engaging with the ratchet-bar, and a wedge-shaped stop with supporting-chain, as will be 15 hereinafter fully described.

Figure 1 is a front elevation, and Fig. 2 is a vertical longitudinal section on line *z z* of Fig. 1.

In the drawings, A represents the window-frame, and B is the upper and C the lower sash. D is the ratchet-bar, which is made of metal, with downwardly-pointing teeth *a*; and E is the hollow metal bar into which the ratchet-bar slides, and which, as shown, is attached to the middle of the upper portion of the window-frame, while the ratchet-bar is attached to the middle of the bottom portion of the sash. In the front of the hollow bar E is an opening, *b*, in which is pivoted a pawl, F, whose lower end engages with the teeth of the ratchet-bar and holds the sash in elevated position. This pawl is provided above its fulcrum with a thumb-piece which projects through the opening in the hollow bar, and behind which thumb-piece is arranged a spring, 35

c, that holds the lower end of the pawl engaged with the ratchet-teeth. Now, when the lower sash is raised, its ratchet-bar is forced up into the hollow bar, where the ratchet-teeth are engaged by the pawl, which thus sustains the 40 sash in any position.

To lock the sash so that it cannot be raised, a wedge, G, is provided, which is conveniently connected to the hollow bar E by a chain, H, and this wedge is designed to be dropped behind the projecting thumb-piece of the pawl F, where it fits into the open space in the hollow bar, and by preventing the pawl from moving out of the way of the ratchet-teeth it prevents the raising of the sash. 45

As shown, my devices are applied to the middle stile of the window-sash; but they may just as well be applied to the side. When attached to the side of the window, the hollow or grooved bar is to be only five inches in 55 length, with a projecting piece at each end or back containing a screw-hole to fasten to the side of the window-frame, and the rack-bar goes through this five-inch bar.

Having thus described my invention, what I 60 claim as new is—

The combination of the ratchet-bar D, the hollow bar E, with opening *b*, the spring-pawl F, pivoted in said opening, and the locking-wedge G, substantially as shown and described. 65

HARRY I. WILLIAMS.
